UNITED STATES PATENT OFFICE

EUGEN REICHEL, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY

LOUD-SPEAKER

Application filed December 15, 1924, Serial No. 755,887, and in Germany January 26, 1924.

My invention relates generally to loud speakers and more particularly to that part of the loud speaker which is designed to amplify and direct the sound waves emitted from the electromagnetic receiver or other sound waves source.

An object of the invention is to provide a loud speaker which will amplify all the sound waves within a given frequency band substantially uniformly.

Other objects will be apparent from the following description and claims when considered with the accompanying drawing in which the single figure is a perspective, partly in section, of a loudspeaker embodying the principles of my invention.

A disadvantage of all loud speakers known up till now is that they have a distinct natural period and that consequently some notes were particularly amplified by resonance. The principle of the present invention is to construct a loud speaker which has several natural periods, in order to attain such a resonance curve for the intensity of the sound that a larger range of frequencies is almost uniformly reproduced. This purpose may be attained, for instance, by varying the shape of the horn and, at the same time, using a sounding board with variable adjustment for tuning purposes.

Consequently the loud speaker represents a system of several periodic devices which are coupled to one another. By a proper selection of the resonance frequencies of these single periodic devices, as well as by suitable coupling factors, very differently shaped resonance curves of the loud speaker may be obtained.

According to the invention a loud speaker can, therefore, be constructed which is characterized by a relatively broad resonance curve, so that it is possible to reproduce a certain range of frequencies with about equal intensity. The dimensions of the horn and of the sounding board of the loud speaker shown in the drawing are variable for the purpose of tuning.

The figure of drawing is a perspective view partly in section and partly in elevation of the invention.

Referring to the drawing, the loud speaker consists of a standard 1 provided at its lower end with a flaring base 2 and at its upper end with a chamber 3 and conical sound passage 4 connected therewith and extending through a projection 8. The loud speaker unit 5 which may be the usual electromagnetic receiver is clamped in the chamber 3 by the clamping means 6. The horn 7 is clamped around the projection 8 by means of clamping member 11.

Secured to the base 2 is sounding board 9, which may be of any of the well known types. The sounding board 9 has an adjustable diaphragm 10 for adjusting the natural period of the board.

Claims:

1. In combination, a loud speaker unit including a horn, a sound board physically connected with said horn, and means for varying the natural period of said sound board.

2. In combination, a standard having a base, a loud-speaker unit supported by said standard, a horn supported by said standard to receive the sound waves from said unit, a sound board connected to said base to receive mechanical vibrations corresponding to the sound waves from said unit, and means for varying the natural period of said sound board.

3. In combination, a standard having a base, an opening through said standard, a loudspeaker unit positioned adjacent one side of said opening, a horn for said unit positioned to receive the sound waves from the other side of said opening, said horn having a predetermined natural period, and a sound board having an adjustable member for varying the natural period of the sound board, said sound board being connected to said base whereby mechanical vibrations are transmitted from said horn and standard to said sound board.

4. A mechanical system for the amplification of sound vibrations having the combination of a plurality of resonant members, one of said members being adjustable so as to have a different natural period of vibration.

5. In a device for amplifying sound vibra-

tions, the combination of a resonant base and a horn, said resonant base having independent adjusting means for varying its natural period of vibration.

- 5 6. In a device for translating electrical undulations into sound vibrations and for amplifying the latter, a hollow resonant base having a plunger therein for varying the natural period of the base, a member mounted on the base, a horn mounted on the member and a sound wave producing unit associated with said horn.

EUGEN REICHEL.
